UNITED STATES PATENT OFFICE.

WILLIAM H. MULLINS, OF SALEM, OHIO.

DESIGN FOR A ROOF-FINIAL.

SPECIFICATION forming part of Design No. 24,597, dated August 20, 1895.

Application filed April 1, 1895. Serial No. 544,098. Term of patent 7 years.

To all whom it may concern:

Be it known that I, WILLIAM H. MULLINS, a citizen of the United States, residing at Salem, in the county of Columbiana and State 5 of Ohio, have invented and produced a new and original Design for Roof-Finials, of which the following is a description, reference being had to the accompanying drawing, in which the figure is a perspective view of my invention.

The purpose of this design is the ornamentation of roofs for buildings, my invention residing in the production of a finial, as illustrated, which shall constitute an attractive 15 and fitting terminal for ridge-crestings employed at the apex of buildings, dormers, gables, &c., on the better class of architectural structures, same consisting of the unitary designs for finials made the subject of illustration, having for its leading or characteristic 20 features a body portion, ridge-cap, and terminals, as below set forth.

The design, more particularly described, consists in a body portion 1 of substantially 25 conical form, which merges, by graceful curves, into a vertical horn-like crocket 2 above. The face or forward side of said crocket, formed wholly of convex surfaces, is semicircular in cross-section, is rounded on its

upper extremity, as at 3, and terminates in an 30 overhanging beak 4 at a point back of its vertical center and slightly below the extremity 3. The rear or remaining side of crocket 2 is formed of concave surfaces, which join said convex surfaces at the sides of the figure and 35 end in the beak 4, which they serve to complete. Extending rearwardly from body portion 1 is a horizontal ridge-cap or saddle 5, presenting in cross-section a double-ogee appearance and terminating at its lower edges 40 in parallel side fillets 6, the latter being ornamented by raised volutes 7, as shown. At its front the body portion 1 is bifurcated and equipped with terminals 8, said terminals, like the ridge-cap 5, each presenting a double- 45 ogee cross-section and being ornamented each by corresponding upturned lips or crockets 9. This being a description of my design,

What I claim, and desire to secure by Letters Patent, is—

The design for an ornamental finial, substantially as herein shown and described.

In testimony whereof I subscribe my signature in presence of two witnesses.

WILLIAM H. MULLINS.
